UNITED STATES PATENT OFFICE.

MATTHEW S. CUMNER, OF BROOKLYN, NEW YORK, AND FREDERICK W. GEISSEN-HAINER, OF FREEHOLD, NEW JERSEY.

WHEEL-TRIMMING DEVICE.

Original application filed December 31, 1920, Serial No. 434,194. Divided and this application filed June 8, 1922. Serial No. 566,906.

To all whom it may concern:

Be it known that we, MATTHEW S. CUMNER, a citizen of the United States, and a resident of Brooklyn, Kings County, State of New York, and FREDERICK W. GEISSEN-HAINER, a citizen of the United States of America, and a resident of Freehold, county of Monmouth, and State of New Jersey, have invented certain new and useful Improvements in Wheel-Trimming Devices, of which the following is a specification.

This invention relates to trimmer mechanisms for grinding wheels and is a division of application Serial No. 434,194 filed December 31, 1920.

One of the essentials to the grinding of perfect threads on hobs is that the cutting surfaces of the grinding wheel be in good condition always and at an angle corresponding with the angle between the sides of the finished thread. It is essential also, when steep pitch hobs are cut as by turning the grinding wheel at an angle about a horizontal axis, that the sides of the cutting wheel be properly trimmed to the proper angle with due allowance for the position of the wheel.

This invention has for its object therefore to provide simple, accurate and easily adjustable means for trimming or dressing a grinding wheel in a manner whereby the aims above set forth will be attained.

Further objects will appear from the following specification taken in connection with the drawings forming a part of this application and in which—

Fig. 1 is a plan view of the grinder wheel and a portion of the wheel dressing mechanism.

Fig. 2 is an enlarged plan view partly in sectional detail of the wheel dressing mechanism on the line 2—2 of Fig. 3.

Fig. 3 is a detail section of a portion of the actuating mechanism of the wheel dressing device on the line 3—3 of Fig. 2.

Fig. 4 is a front elevational view on a larger scale of the wheel dressing mechanism.

Fig. 5 is a transverse elevational view of

the wheel dressing mechanism and adjacent parts.

Fig. 6 is a transverse elevation section, corresponding to the view of Fig. 5, but on the line 6—6 of Fig. 4.

Fig. 7 is a detail elevational sectional view of a clamping screw on the line 7—7 of Fig. 5.

Figs. 8, 9 and 10 are details of the longitudinal trimming mechanism for the grinding wheel.

Referring to the drawings, the trimmer mechanism is mounted in conjunction with the grinding wheel, on the same base 6 and moves with the wheel in transverse, arcuate and longitudinal adjustments so that it will be operative in all positions for use in trimming the wheel.

The mounting for the grinding wheel will first be described.

The wheel 50 is carried by a shaft 50^a and is rotated at the desired speed by a belt drive applied to a pulley 81.

The journals 50^b, 50^b of the shaft 50^a are mounted as by clamping fingers 82, 82, pivotally positioned as by the studs 83, 83 and clamped over the journals as by the bolts 84, 84, taking in threaded holes in the lower stationary clamping fingers 85, 85.

The fingers of one of said pairs of clamping fingers, (as for example the left hand pair in Fig. 1) may both be pivotally mounted as at 83 on the arcuate frame 90. The other of said pair of clamping fingers (as for example the right hand pair in Fig. 1) is slidably adjustable in and out transversely between the guiding members 86, 86 (Figs. 5 and 7) and may be clamped in position by the nuts 87, 87. The purpose of this adjustment is to align the axis of the grinding wheel with the axis of the rotating piece to be cut or at any desired angle thereto.

The frame 90, carrying the journals in which the shaft 50^a revolves, is mounted on arcuate guides 88 and may be adjusted about a horizontal transverse axis passing through the center point of the cutting wheel. This adjustment is made by a screw

- 91, being itself held from longitudinal movement by a stud 91^a taking in a groove 91^b in the shank of the screw. The thread 91^c of the screw meshes with a thread cut 5 on the arcuate periphery of the frame 90.
- A bolt 89 whose head rides in an arcuate slot in the frame 90 may be clamped by reason of the nut 89^a and frictionally hold the frame 90 in set position.
- 10 The purpose of this adjustment is to incline the cutting wheel 50 as desired for the purpose of cutting very steep pitch hobs.
- 15 A longitudinal adjustment of the grinding wheel relatively to the carriage 6 may be obtained by reason of the guides 92 and the clamping screws 93, 93.
- 20 A transverse movement of the carriage 6 may be obtained in the usual well known manner, as illustrated in the parent application referred to, of which this application is a division.
- The trimmer mechanism for the grinding wheel will next be described.
- 25 There are two trimming tools 94 and 95, one for each side of the wheel 50, and they are moved alternately into operating position by oscillation of the handle or lever 100.
- 30 Each trimming tool is preferably mounted in a square bar 96, which is toothed on one edge and in mesh with a corresponding feed gear 97 or 98.
- 35 The gear 97 is in mesh with a gear 101 and the gear 98 is in mesh with a gear 102, each of said gears 101 and 102, having a shaft on which is affixed another gear as 101^a and 102^a respectively meshing with an internal gear or rack 99 which may be swung about a fixed center by the manipulation of the handle 100.
- 40 It is apparent that when the handle 100 is swung and the rack 99 turned, the gears 97, and 98 will both rotate in the same direction but as the bars 96, 96 are in contact on opposite sides of their actuating gears, 45 one will be fed forward and the other drawn back. For example, if the handle 100 is swung to the left (Fig. 2) the trimmer 94 will be drawn back and the trimmer 95 will be fed outward. With the handle 100 thrown to the right, the tool will be drawn back and the tool 94 will be fed outward. In this way, the trimming of the wheel 50 is done alternately on one side and then on the other side.
- 50 To provide for variation of the angle between the trimmers, each tool is mounted on its own plate 94^a and 95^a respectively and is clamped to the common base 105 by bolts 94^b and 95^b respectively operating in arcuate slots in the common base.
- 55 Each plate has a micrometer adjusting screw 94^c, 95^c respectively in mesh therewith, each screw being mounted in a swinging cylinder 94^d, 95^d, respectively.
- 60 To vary the angle of trimmer 94, for example, with the center line of the grinding wheel 50, the clamping screw 94^b may be loosened, a set screw 103 loosened (Fig. 3) whereby a spring 104 in the shaft of the gear 101 will raise the gear 101^a out of mesh 70 with the rack 99 and raise the gear 101 into a recess 106.
- The adjusting screw 94^c may then be turned by means of the knurled head and the screw being fixed will actuate the co-75 operating arcuate plate 94^a as desired. The bolt 94^b may then be clamped, the set screw 103 tightened until gears 101 and 101^a are in mesh with their cooperating parts.
- It is apparent, therefore, that the wheel 80 may be trimmed to the same angle on each side or may be, in fact, distorted by trimming the two sides to different angles as may be necessary when steep pitch hobs are 85 to be ground.
- A forward and back adjustment of the trimmers and their mounting, towards or away from the wheel 50 may be made by means of the transverse adjusting screw 126 which is fixed in the plate 107 and threaded 90 in the base 105. Rotation of the screw 126 will therefore move the base 105 transversely.
- The base 107, carrying the trimmers and all adjustments thereof, is pivotally mounted 95 as by arms 108, 109, to a lug 110 on the journal bearing plate 90 by means of a pin 111 so that it may be bodily swung over backwards in a transverse arc and wholly removed from the vicinity of the grinding 100 wheel.
- A trimmer is also required for flattening off the edge of the grinding wheel when hobs are cut as hob teeth in general have a flat edge in place of a sharp edge such as is 105 frequently found in screw threads. We have therefore devised a longitudinal wheel trimmer to be mounted in conjunction with the face trimmers already described and on the same base plate.
- The mounting for the longitudinal trimmer 117 (Figs. 8, 9 and 10) comprises a bracket 112 affixed to the surface of the plate 90 as by the screws 112^a, 112^b. A casing 113 is pivotally affixed to the bracket 112 as by 115 the screw 114. By tightening the screw 114 the casing 113 may be held in any desired position but a stop pin 115 is provided against which a projecting pin 116 of the casing strikes and limits the downward motion of the casing to position the trimming tool 117.
- As in the case of the face trimmers, the trimmer 117 is mounted on a square bar 118 longitudinally slidable in the casing 113 and 125 toothed on a portion of one edge as at 119. A gear 120 actuated by a pin 121 serves to feed the trimmer longitudinally across the wheel face.
- A transverse adjustment of the trimming 130

tool 117 is provided at the end of the bar 118. A frame 122 has a track or guide 123 on which the tool carrier 124 slides by the action of the screw 125 fixed in the frame 122 and threaded into the tool carrier 124. Rotation of the screw 125 therefore feeds the tool in and out transversely.

It is apparent that the longitudinal trimmer may be swung into position when the other trimmers are swung back and vice versa.

The operation of the trimming mechanism has been described above part by part but it may be said that the position of the work to be ground may be made in the usual fashion.

Although one specific embodiment of the invention has been particularly illustrated and described, it will be understood that the invention is capable of modification and that changes in the construction and in the arrangement of the various cooperating parts may be made without departing from the spirit or scope of the invention as expressed in the following claims.

What we claim is:—

1. In a device of the character described, a grinding wheel, a trimming device comprising a support, a plate pivotally affixed to said support having arcuate guides, trimming tool carriers adjustably affixed in said guides, whereby said carriers may be angularly adjusted relative to the axis of the grinding wheel, adjusting means for said carriers, a tool bar slidably mounted in each carrier having a toothed edge, a rack, an operable connection between said rack and each bar, and actuating means for said rack whereby each bar is slidably actuated.

2. In a device of the character described, a grinding wheel, a trimming device comprising a support, a plate pivotally affixed to said support having arcuate guides, trimming tool carriers adjustably affixed in said guides, whereby said carriers may be angularly adjusted relative to the axis of the grinding wheel, adjusting means for said carriers, a tool bar slidably mounted in each carrier having a toothed edge, a rack, an operable connection between said rack and each bar comprising a series of gears adapted and arranged to actuate said bars in substantially opposite directions simultaneously, and actuating means for said rack whereby each bar is slidably actuated.

3. In a device of the character described, a grinding wheel, a trimming device comprising a support, a plate pivotally affixed to said support having arcuate guides, trimming tool carriers adjustably affixed in said

guides, whereby said carriers may be angularly adjusted relative to the axis of the grinding wheel, adjusting means for said carriers, a tool bar slidably mounted in each carrier having a toothed edge, a rack, an operable connection between said rack and each bar, means by which the operable connection between said rack and each bar may be disengaged during the adjustment of said carriers, and actuating means for said rack whereby each bar is slidably actuated.

4. In a device of the character described, a grinding wheel, a trimming device comprising a support, a plate pivotally affixed to said support having arcuate guides, trimming tool carriers adjustably affixed in said guides, whereby said carriers may be angularly adjusted relative to the axis of the grinding wheel, adjusting means for said carriers, a tool bar slidably mounted in each carrier having a toothed edge, a rack, an operable connection between said rack and each bar, actuating means for said rack whereby each bar is slidably actuated, and means for rendering inoperable the connections between the rack and said bars.

5. In a device of the character described, a grinding wheel, a trimming device comprising a support, a plate pivotally affixed to said support having arcuate guides, trimming tool carriers adjustably affixed in said guides whereby said carriers may be angularly adjusted relative to the axis of the grinding wheel, adjustment means for said carriers, a tool bar slidably mounted in each carrier having a toothed edge, a rack, an operable connection between said rack and each bar comprising a series of gears adapted and arranged to actuate said bars in substantially opposite directions simultaneously, actuating means for said rack whereby each bar is slidably actuated, and means for rendering inoperable the connections between the rack and said bars.

6. In a device of the character described, a base, a grinding wheel supported thereon, a plate pivoted on said base on an axis substantially parallel to the wheel axis, a plurality of angularly disposed face trimmers mounted on said plate and movable to trim the faces of said wheel, a guide carried by said base and pivoted on an axis substantially at right angles to the wheel axis, and a reciprocable edge trimmer mounted in said guide and movable across the edge of the grinding wheel.

In witness whereof, we have hereunto set our hands this 6th day of June, 1922.

MATTHEW S. CUMNER.
FREDK. W. GEISSENHAINER.
